MECHANICAL ROSTER CHART

Thor A. Rylander and Edmund N. Alley, Jr.,
Newcastle, N. H.

Application January 20, 1943, Serial No. 473,022

1 Claim. (Cl. 40—65)

(Granted under the act of March 3, 1883, as
amended April 30, 1928; 370 O. G. 757)

The present invention relates to what may be described as a mechanical roster chart for posting "shifts" of guard forces or operating personnel, which may be used in many different kinds of plants, where it is necessary to post patrols, watches, and the like, to prevent loss of time, over-lap of duty, and eliminate if possible, any return to duty by members of the personnel without having a minimum of time off, or release from duty by said personnel.

A "figured" schedule of time, giving the "hours," "days," etc., is first made out on suitable cards, called "schedule cards," and the names of the personnel are prepared preferably on separate pieces of cardboard or the like, and said names may be set out by means of the present device in proper relation to the desired "hours" and "days" of service, when it is desired that particular individuals shall be on duty, or in service.

By means of the present device the successive "dates" when the particular schedule cards, and the particular individuals are intended to be on duty or in service, may be changed according to the date or day and hour when the schedule is in effect, by merely mechanically changing the position of the name and date cards of the device (using an easily and quickly mechanically operated inner movable member), with relation to the holders in which are posted the schedule cards, and then locking the movable member in proper relative position, by means of a very simple locking device. All of which will be more thoroughly explained as the description proceeds herein.

The arrangement of date cards, schedule cards and "personnel" names may be arranged for a weekly schedule, or a two weeks schedule, or a monthly schedule as desired, and more than one group of working personnel may be posted on the face of the device in hand if desired.

When the personnel and schedule cards are adjusted for any particular day, the said arrangement of personnel and schedule hours may be changed for a succeeding date very quickly by merely moving the central movable member carrying the date and personnel cards, without any rearrangement of the schedule cards, and then locking the central movable member in the proper selected position.

This chart can be used to check ahead for possible events of note or interest, and also to check back to determine who was on duty or in service on any particular post or section, on any particular past date and time of watch or service.

The arrangement of the parts of the device in

hand are particularly ingenious and convenient both for use, and for purposes of manufacture, and the nature of the constructional parts of the device will be fully described in the specification hereunder.

In the accompanying drawings forming part of the present specification:

Fig. 1 is a face or front view of the present invention as seen in elevation.

Fig. 2 is a bottom view of Fig. 1.

Fig. 3 is a top plan view of Fig. 4, a centrally disposed movable and slideable member forming part of the present device.

Fig. 4 is a front elevation of said centrally disposed, movable and slideable member just described.

Fig. 5 is a bottom view of Fig. 4.

Fig. 6 is an enlarged top plan view of the supporting holders taken on line 6—6 of Fig. 4 and is typical of said name and date card holders used on the device.

Fig. 7 is a partial side view of a name or date card holder and the rack used therein, taken from the left of Fig. 4.

Fig. 8 is a transverse horizontal section of an operating and locking screw and associated parts taken on line 8—8 of Fig. 1.

Referring to the drawings the device in hand comprises a hollow box-like case or cover 1, which may be made of any suitable material such as plywood, composition, or metal as desired. In the type of device shown in the drawings the cover or case 1 is made preferably of a composition or pressed material, the boundary edges 24 of which are made of bent metal to form a substantial outline for the case, as well as for the purpose of presenting an attractive appearance for the device. An aperture 26 is formed in the bottom edge 25 of the case 1, which permits the slideable insertion of a centrally disposed slideable and movable member 18, which is shown in Figs. 4 and 5 of the drawings.

In the front face of the case 1, are a number of apertures 4, 5, 6, 8, the size and location of which are shown in the drawings, and the purpose of which will presently appear below. Also a vertical slot 10 is formed in case 1 which is preferably outlined or surrounded on the outer face of the case by a metal border plate 31, as shown, in order to provide a smoothly operating face for the handle or operating pin 11 mounted on the part 19, which last is rigidly mounted on the movable slide member 18.

On the face of the case 1 are mounted a number 55 of preferably metal frames 3, 7, 9 spaced a dis-

tance from the front wall of the case, for the insertion of schedule cards 17, 14 and 16 respectively.

The cards may be preferably slid downward from the top of the metal frames 3, 7, and 9 in each instance. A name-plate 2 of attractive appearance, with or without a design thereon may be added to the front face or wall of case 1.

Associated with the box-like case 1 is the insertable centrally positioned movable member 18 which is composed preferably of a flat composition material, similar to the material of the case or cover 1. This member 18 is adapted to slidably enter the slot 26 formed in the bottom of the case 1, as clearly shown in Figs. 1 and 2 of the drawings. On the face of the member 18 are a series of "date" and "name" holders 27, 28, 29, 30 for name cards, date cards and the like. Each of these holders are preferably similar in construction and each comprise the following parts. A slotted rack such as 22, the construction of which is clearly shown in Figs. 6 and 7 of the drawings is used. The front face of the racks are provided with slots 32, 32 which extend transversely the full width of each rack 22 (see Figs. 6 and 7), for the purpose of slidably inserting name or date cards 12, 12', 13, 15 as desired. The racks 22, 22 are each held in place on the front wall of the movable member 18 by means of two metal bars 20, 21 and secured by rivets 23, 23 to said member 18, as clearly shown in Fig. 6 of the drawings.

The flat metal bar 20 has an inwardly-turned portion 33 shown in Figs. 4 and 6, the purpose of which is to form a "stop" for the date and name cards 12, 12', etc., as is at once understood. The bar 21 is merely a flat bent bar to enable the date and name cards 12, 12', etc., to be inserted in the slots 32, 32 from the left side of the holders 27, 28, 29, 30 as seen in Fig. 4 of the drawings.

With reference to the handle or operating pin 11 above mentioned, same is preferably screw-threaded into the metal part 19 as shown in Fig. 8 of the drawings, and it will be seen that if the screw is loosened somewhat in the screw-threaded seat 34, that the clamping effect of the bottom 35 of pin 11 is released and the central member 18 may then be raised or lowered in relation to the cover or case 1 and thereby the relationship of the "name" and "date" cards 12, 12', 13, 15 may be varied with respect to the schedule cards 14, 16, 17 as is understood.

When any desired position is reached for the name and date cards with relation to the schedule cards, the operating and locking pin 11 is turned in its seat until the under surface 35 thereof locks the movable member 18 in desired position with respect to the front wall of the case 1. The slot 10 permits a variety of positions for the member 18 with respect to the case 1.

The use and operation of the device is as follows:

A "schedule" card is first made out such as 17, 14 or 16 for each of the metal frames 3, 7, 9 to meet the requirements of any unit or establishment, covering posts, patrols, watches, etc., so there will not be any over-lap of duty or loss of time, and to eliminate if possible any return to duty of personnel without having a minimum amount of time off, or release from duty. The "figured" schedule cards are placed in the proper and suitable holder frames 3, 7, 9 on the face of the case 1. If there is more than one section

for the roster chart each section maintains its separate schedule and headings and the "schedule" cards made accordingly.

The names of the individuals or groups of personnel who are to be on duty, or in service during the various watches or periods of service, are typed or printed on paper or card-board strips and inserted in the slots 32, 32 of the name-card holders 27, 29 or 30 (see Fig. 4 of the drawings), and placed in pre-arranged working relation with reference to the schedule cards as is at once understood.

The section holder 28, Fig. 4, is reserved for the dates the schedule cards are to be in effect, and "date" cards or slips on card-board preferably are made for insertion in the slots 32, 32 of the rack 22, which is used in the section holder 28. One of such dates always appears through the opening 5, Fig. 1, so the date on which the pre-arranged schedule, and personnel cards are to be in effect is readily seen. The dated slips are placed in order in the rack 22, mounted in section holder 28, commencing at the top, for every week, if on a weekly change of schedule, every fourteen days, if on a two weeks schedule of operation, and every 28 days, etc., if on a monthly schedule.

The slideable centrally-positioned member 18 is then inserted through the aperture 26 in the bottom of the cover case 1, and pushed upward, until the operating and locking handle 11 can be screwed into the part 19. The member 18 is next adjusted to the date which is required in the slot or aperture 5, when the proposed personnel and schedule cards are desired to be in effect, and the locking pin or handle 11, is screwed into tightened position and the member 18 locked against movement with relation to the case 1. With the "personnel" cards in alignment with the "hours" data, the schedule is now in effect, giving the "hours," the "day," and the "personnel," which are to be in service or on duty, and for the particular date shown in aperture 5, as is at once seen.

The next change in schedule is made by moving the slideable center member 18 by means of the operating and locking pin 11 in the slot 10, to any succeeding position desired with reference to the schedule cards and cover case 1 as is at once evident. The date in the slot 5 it is seen is the usual controlling factor in the adjustment of the member 18 with reference to the case 1, as the "personnel" and the "schedule" cards are made out primarily with the said exposed "date" card in view.

This roster chart can be used to check ahead for possible events of interest or particular note, and also to check back to determine who was on duty, or in service at any particular post or time, on a past date or time of watch or service.

From which it is seen that we have provided a very ingenious and useful device for the purpose intended and above described.

The invention described herein may be manufactured and used by or for the Government of the United States of America for governmental purposes without the payment of any royalties thereon or therefor.

We claim:

In a name holder device, a supporting rear wall, a rack having a plurality of horizontally disposed transverse slots formed in the front face of same, each adapted to hold a name card therein, means for holding the rack and the name cards in position on the said rear wall, compris-

ing a bent flat metal bar with a pair of opposed L-shaped ends thereon, enclosing the front face of said rack, and a second bent flat metal bar with a pair of opposed L-shaped ends thereon enclosing the face of said rack, and a bent and inwardly-turned side wall formed along the length of said bar, adapted to form a stop for the ends

of the name cards which are mounted in the slots of said rack, and means in the L-shaped ends of the metal bars for securing the latter to the rear supporting wall.
